COMBINED GUARD RAIL AND CONTROL PANEL FOR A COOKING RANGE OR THE LIKE

Frank Breckenridge, Whittier, and Thomas D. Tweedie,
Monrovia, Calif., assignors to O'Keefe & Merritt Com-
pany, Los Angeles, Calif., a corporation of California

Application April 8, 1958, Serial No. 50,383

Term of patent 14 years

(Cl. D81—25)

Fig. 1.

Fig. 2.

Fig. 1 is a front perspective view of a combined guard rail and control panel embodying our new design; and,

Fig. 2 is a fragmentary cross-sectional view of the line 2—2 of Fig. 1 in the direction of the arrows illustrating the surface configuration of the control panel portion of the combination.

The dominant features of the design reside in the portions shown in full lines.

We claim:

The ornamental design for a combined guard rail and control panel for a cooking range or the like, as shown and described.
